UNITED STATES PATENT OFFICE.

FRANK E. BUTTERFIELD, DECEASED, LATE OF WAKEFIELD, MASSACHUSETTS, BY
EUGENE M. BUTTERFIELD, ADMINISTRATOR, OF WALTHAM, MASSACHUSETTS, AS-
SIGNOR TO BECKWITH BOX-TOE COMPANY, OF DOVER, NEW HAMPSHIRE, A CORPO-
RATION OF MAINE.

BOX-TOE AND BLANK THEREFOR.

1,124,694.

Specification of Letters Patent.

Patented Jan. 12, 1915.

Original application filed August 7, 1911, Serial No. 642,690. Divided and this application filed August 2,
1913. Serial No. 782,697.

To all whom it may concern:

Be it known that FRANK E. BUTTERFIELD, late of Wakefield, in the county of Middlesex and State of Massachusetts, deceased, did invent certain new and useful Improvements in Box-Toes and Blanks Therefor, of which the following is a specification, this application being a division of the application filed August 7, 1911, by Frank E. Butterfield, Serial No. 642,690.

This invention relates to the manufacture of boots and shoes, the toe portions of the uppers of which are stiffened by a box-toe formed during the operation of lasting the toe portion of the upper instead of being formed or molded prior to the lasting operation.

The invention has for its object to enable a properly stiffened and durable forepart to be produced more perfectly and quickly than heretofore, and to reduce to the minimum the cost for producing a stiffened upper forepart.

The invention consists in the improvements which I will now proceed to describe and claim.

Of the accompanying drawings which form a part of this specification,—Figure 1 represents a side view of a box-toe blank used in practising the invention. Fig. 2 represents a longitudinal section of a shoe upper before lasting, the said blank being incorporated in the upper and the upper being shown applied to the last without being conformed thereto. Fig. 3 represents a view similar to Fig. 2, showing the upper conformed to the toe portion of the last. Fig. 4 represents a side view of a portion of an unlasted vamp, and a box-toe blank and a toe cap attached thereto, a portion of the toe cap being broken away to show a portion of the box-toe blank. Fig. 5 represents an enlarged section on line 5—5 of Fig. 4.

Similar reference characters indicate the same or similar parts in all the figures.

In the drawings,—12 represents the vamp portion of a shoe upper and 13 represents the usual or any suitable toe cap attached by stitches 14 to the vamp and adapted to be

lasted over the toe portion of the upper in 50 the usual manner.

20 represents a last.

15 represents a box-toe blank adapted to be conformed to and cover the toe portion of the upper surface of the last and to be 55 bent or crimped inwardly over the marginal portion of the bottom of the toe portion of the last. The blank 15 may be attached at one edge to the vamp 12 by zig-zag stitches 14, the blank being at the inner 60 side of the toe cap. If desired, however, the blank may be placed loosely on the inner side of the toe cap and interposed between the toe cap and the toe portion of the vamp in case the latter is formed to cover the upper surface of the toe portion of the last. I prefer, however, especially in McKay sewed shoes to stitch the blank to the vamp, as shown by Figs. 4 and 5.

The blank 15 is made of a fibrous absorbent material, preferably felt, although it may be composed of one or more layers of textile fabric, if desired. The material of the blank in any case, must be of such nature that it is capable of absorbing a fluid 75 stiffening material or composition.

In carrying out my invention, I saturate the blank with a composition or material having a relatively low melting point whereby it may be softened by a degree of heat 80 which is not injurious to the upper leather, and yet be stiffened by cooling. A suitable composition is provided, for instance, by making an alcohol solution of shellac composed of eight pounds of shellac and one 85 gallon of alcohol, and mixing with this a solution of borax dissolved in hot water, suitable proportions being one ounce of borax to two ounces of water.

The blank 15 having been saturated with 90 the above described composition and dried, becomes relatively hard and stiff and is in this condition when assembled with the other parts of the upper. I use the term upper in its comprehensive sense as including 95 the vamp, the toe cap and the blank 15.

The parts of the upper having been assembled in suitable relation to the last, as

indicated by Fig. 2, I soften the blank by heating it to a degree which preferably is not injurious to the leather parts of the upper, the degree of heat employed being (in 5 the case of the particular composition specified) preferably from 110 to 120 degrees F. The composition above described has a relatively low melting point so that it is adapted to be softened to render the blank limp and flexible, by a degree of heat such as that 10 above indicated, this heat being free from liability to injure the leather. While the blank is softened by heat, I conform the entire toe portion of the upper, including the 15 blank, to the toe portion of the last by the usual lasting operation, the blank 15 conforming readily and accurately to the surfaces of the last against which it is pressed, and receiving therefrom the form of a box-toe 15^a. (Fig. 3).

After the lasted portion has been suitably secured, either temporarily or otherwise, to the last, the box-toe 15^a is allowed to stiffen by cooling. Owing to the relatively low degree of heat required to soften the blank, the box-toe into which the same is converted by the lasting operation, is stiffened and hardened in a correspondingly brief period, and will retain its shape during wear of the 30 shoe. I find in practice that in making a McKay sewed shoe it is practicable to remove the last from the shoe immediately after the upper has been lasted and the outer sole laid, the box-toe having been sufficiently stiffened by cooling at the end of the sole-laying operation.

I do not limit myself to the above described composition, there being many other materials or compositions which may be 40 used with the same results. In any case, the stiffening material should be capable of resisting the heat of the body so that it will not be softened by bodily heat when in use. Moreover, the composition should be practically insoluble in water so that it will not 45 be softened by dampness to which it is likely to be subjected when in use.

I am aware that a box-toe blank made of 50 felt has been treated with a solution of shellac and has been softened by means of a solvent of shellac, such as alcohol, and while so softened has been conformed to the toe portion of a last by the operation of lasting the upper. The box-toe formed by lasting the wet blank has to be thoroughly 55 dried to stiffen it, the drying operation consuming much more time than is required to stiffen the box-toe by cooling in accordance with my invention. Moreover, the employment of a solvent is objectionable on account of its cost and its combustibility.

It is obvious that a box-toe blank treated 60 as above described, is adapted to be softened without injury to the other portions 65 of the upper and without injury to the ma-

terial of the blank itself by the application of heat thereto, there being no liability of scorching or weakening the material of the blank by excessive heat.

I have omitted the usual cloth lining in 70 Figs. 2 and 3, for the sake of simplicity and clearness.

16 represents a reinforcing strip of thin cloth, which covers the joint formed by the abutting edges of the vamp 12, and blank 75 15, the portions of the zig-zag stitches 14^a which pass through the vamp and blank also passing through the reinforcing strip, as shown by Fig. 5. The strip 16 is laid on the inner surfaces of the vamp and blank, 80 as shown by Figs. 2 and 3. Fig. 2 shows an inner sole 19 applied to the last 20. Fig. 3 shows the toe portion of a completed McKay sewed shoe, removed from the last 85 and provided with an outer sole 21 attached in the usual manner.

I claim:

1. A shoe having a box toe consisting of a single thickness of absorbent material containing stiffening composition or material capable of being softened by a degree of heat which is not injurious to leather, but not of being softened by the heat experienced during ordinary wear, said fibrous material, with the stiffening material therein, being in the position into which it was lasted when said stiffening material was heated and softened.

2. As an article of manufacture, a box-toe blank of absorbent material containing a stiffening material adapted to be softened while dry, by a temperature of approximately 110° F., and adapted to resist softening by a lower temperature, substantially as described.

3. As an article of manufacture, a box-toe blank of an absorbent material containing a dry stiffening material, adapted to be softened by a temperature of approximately 110° F., and adapted to resist softening by a lower temperature.

4. A box-toe blank prepared for lasting in a shoe consisting of a sheet of fibrous absorbent material impregnated with a stiffening material which is capable of being softened and rendered plastic by heat and of hardening upon cooling, said blank being in a heated plastic condition in which it may be readily conformed to the shape 115 of the last during the lasting operation.

5. A shoe upper prepared for lasting having assembled therewith a toe stiffener blank in a heated plastic condition, said blank consisting of a sheet of fibrous absorbent material impregnated with a stiffening material which is capable of being softened and rendered plastic by heat and of hardening upon cooling so as to stiffen the toe blank when the shoe is completed.

6. As a new article of manufacture, a

stiffener for boots and shoes consisting of a sheet of fibrous material impregnated with a stiffening material which is capable of being softened when heated so as to be lasted in a shoe when so heated, which is capable of setting on cooling, and which when set is unaffected by moisture or the heat of the human foot.

In testimony whereof, I have affixed my signature, in the presence of two witnesses. ¹⁰
